UNITED STATES PATENT OFFICE.

WILLIAM S. PROSSER, OF AUBURN, CALIFORNIA.

FEEDING STRAW AS FUEL TO FURNACES.

SPECIFICATION forming part of Letters Patent No. 279,012, dated June 5, 1883.

Application filed September 8, 1882. (No model.)

To all whom it may concern:

Be it known that I, WILLIAM S. PROSSER, of Auburn, in the county of Placer and State of California, have invented certain new and useful Improvements in Feeding Straw as Fuel to Furnaces, of which the following is a full, clear, and exact description.

This invention is mainly designed to be applied to straw-burning traction-engines—such, for instance, as are used in conjunction with combined “headers” and “thrashers” that are moved over the field and cut and thresh the grain at one operation.

The invention consists in a device or apparatus for automatically feeding the straw to the furnace of the engine, substantially as hereinafter described.

Reference is to be had to the accompanying drawings, forming part of this specification, in which similar letters of reference indicate corresponding parts in all the figures.

Figure 1 represents a side elevation of an automatic straw-feeding device applied to the furnace end of a threshing-engine in accordance with my invention. Fig. 2 is a longitudinal vertical section of said straw-feeding device in part, and Fig. 3 a transverse section thereof on the line *x* *x* in Fig. 2.

A in the accompanying drawings indicates a long and narrow feed box or tube, made either of wood or metal, or both. Its length and dimensions in cross-section will vary according to circumstances. It is open at its opposite ends, and, when applied to a combined header and thrasher, its lower end will be run under the thrasher to catch the straw as it falls, said box being set inclining upward from its receiving end to its delivery end. Its upper or delivery end connects with the fire-box or furnace B of the traction-engine. Fitted to this box—say in and along the upper portion of the same—is a bar or slide, C; or there may be any number of such bars. This bar has a reciprocating movement in direction of the length 45 of the box A, and is so operated by motion derived from the engine—as, for instance, by a belt, *b*, a wrist-pin, *c*, on a pulley, *d*, driven by the belt and a connecting-rod, *e*, or by any other suitable devices.

Means should be provided for arresting the motion of the bar C without stopping the engine when it is not required to feed straw to

the furnace. This may be done by a belt slackening and tightening device applied the belt *b*; and to prevent the fire from following the straw in the feed-box said box may have a flap or slide for closing its entrance when stopping the feed.

Pivoted to the bar C are a series of tines or forks, D, arranged to project down within the box A, and having their drop motion controlled by suitable stops and hung so as to admit of their operation, substantially as follows: When the bar is moved downwardly or back these tines D are pushed up or to one side by the pressure of the straw in the box, as shown by dotted lines in Fig. 2; but when the bar is moved in an opposite direction said tines drop, or may be thrown out by springs, to catch in the straw and push it up along toward the end of the feed-box A, which is attached to the front of the furnace, and so supply the fire-box with the straw fuel.

The furnace may have a separate door arranged below the feed-box A for the purpose 75 of clearing the fire, or said box may be arranged to push on one side and leave an opening into the furnace, or both.

For ordinary straw-burning engines running a thrasher the feed-box A may be provided 80 near its one end with a light rack, into which the straw is thrown; or the bar C may be made flexible or hinged, as at *f*, and the hinged rear continuation, C', of said bar, having a vertical movement, be provided with teeth D, so that 85 when laid on top of a straw pile it will draw it into the box. The box A may also be pivoted or hinged so as to admit of its swinging around and reaching all parts of the straw pile.

On the inside or bottom of the feed-box A 90 may be arranged a series of tines or teeth, E, between which the hinged tines D work, and which will assist in keeping the straw from being drawn back when the reciprocating bar C moves backward. The teeth E may, however, in 95 some cases be dispensed with. However, in fact, the details of this automatic straw-feeder may be arranged, the application of a mechanical feeder to a threshing and especially to a traction engine, actuated by said engine, will be 100 found very serviceable, and enable the engineer, with but a small amount of labor, to dispense with the services of a fireman, while the straw will be fed into the furnace in a much

more uniform and efficient manner than has heretofore been done.

When the feed-box A is provided near its one end with a tight rack into which the straw is thrown, as hereinbefore referred to, then the bar C and its continuation C' should be hinged or united with each other by short intermediate-pivoted rocking levers, and the teeth or tines D' should be arranged to project upward.

10 Having thus described my invention, what I claim as new, and desire to secure by Letters Patent, is—

The combination, with the straw-feed box A and one or more reciprocating bars, C, having pivoted tines D, of a flexible rear continuation, C', of said bar, provided with teeth D', essentially as and for the purposes herein described. 15

WILLIAM S. PROSSER.
